CORRECTIVE EXERCISING APPARATUS

Eric Barkschat, Chicago, Ill.

Application June 17, 1953, Serial No. 362,188

9 Claims. (Cl. 272—83)

The condition of many people suffering from ailments that disable them to a greater or lesser extent can be improved through corrective exercises.

The object of this invention is to provide an exercising apparatus with which the user may effectively perform coordination and endurance exercises for the muscles of the upper extremities, the shoulder, chest, back, abdominal and hip muscles and to a great extent for the muscles of the lower extremities and also to limber up wrist, elbow, and shoulder joints, the joints of the lower extremities as well as to limber up a stiff back.

A further object of the invention is to produce the aforesaid apparatus in such a form that it requires only a few small, simple and inexpensive parts; the whole occupying so little space that the user may easily take them along if he is to be away from his home or other place where he normally uses them, and being easily installed wherever the apparatus is to be used.

In its preferred form, my improved exerciser consists of a little bracket adapted to be attached to a wall or other stationary, vertical member, together with a pair of handled springs which are adapted to be hooked onto the bracket in a variety of ways to anchor them at one end; the handles being gripped and manipulated by the user to stress the springs during the performance of prescribed exercises.

The various features of novelty whereby the present invention is characterized will hereinafter be pointed out with particularity in the claims, but, for a full understanding of the invention and of its objects and advantages, reference may be had to the following detailed description taken in connection with the accompanying drawing, wherein:

Figure 1 is a perspective view of the wall bracket member of my new apparatus;

Fig. 2 is a front view of the bracket, with a pair of manually-operable spring devices mounted on the bracket in positions adapted for carrying out certain of the series of possible exercises; and

Fig. 3 is an edge view of one of the spring devices.

Referring to the drawing, A represents a bracket and B, B are two manually operable spring devices adapted to be interlocked with the bracket in various ways.

The bracket comprises a base member adapted to be fastened to a wall or the like, together with a plurality of bars mounted thereon. In the particular arrangement shown, the bracket is composed of three pieces of heavy, flat strip material. The first of these pieces is a U-shaped part of which arm 1 forms part of the base, while arm 2, well in front of and shorter than arm 1, is supported by the cross element 3 of the U. An angle member 5 formed of wings 4 and 5, underlies element 3; wing 5 lying flat against and being welded to element 3, whereas wing 4 is in the same plane as element 1 of the U and, with it, forms the base. Two holes 6, 6 in the base are adapted to receive screws to fasten the bracket to a wall or other support. Standing on edge upon element 3, just behind and in contact with and welded to element 2 is a

2

cross bar 7. Short end sections 8, 8 of the cross bar are bent back at right angles. The bracket is symmetrical with respect to a central, vertical plane extending from front to rear.

Each spring device comprises a strong spiral spring 9 formed of flat strip material, flat-wound and having only a few turns so as to leave the center of the spiral open. The inner end of the spring terminates in a long straight section 10 that parallels but is spaced apart from a diameter of the spring; section 10 extending in both directions from a plane at right angles to such diameter and intersecting the center of the spring. The free end of section 10 is bent back upon itself to create a deep hook 11 adapted to fit over either of the long edges of elements 2, 7 and 8. The outer end 12 of each spring extends tangentially and terminates in a laterally-bent piece 13 that is intersected by and stands at right angles to the plane in which straight section 10 at the inner end of the spring lies. Thus the dimension of the spring at right angles to a plane containing a diameter of the spring, is no greater than the width of the strip material from which the spring is made; or, in other words, the spring is of the clock spring type.

A grip or handle 14, that need be no longer than the width of a hand, is fastened at one end to piece 13 at the extreme outer end of the spring, with the axis thereof near and parallel to the plane of the straight inner section 10 of the spring.

In the use of a spring device it is slipped lengthwise of and onto any one of the bars 2, 7 and 8, with its hook interlocked with either long edge of such bar. Thus the spring becomes anchored to the selected bar against bodily rotation thereon. Therefore, if the handle is pushed or pulled in the plane of the spring, the spring is stressed. The handle may be swung through an angle of more than 180° in the direction to tighten the spiral; the resistance increasing progressively and rapidly throughout the entire range of this swinging movement.

While the size of the various parts may vary, I have found that the spring need not be over three inches in diameter and contain only about two and one half complete turns, when the stock from which it is made measures one sixteenth inch by one inch in cross section; the entire device, including the handle, being less than eight inches long. Spring tensions adapted to the needs and strength of a user may be made available through varying the gauge and width of the stock used in the springs.

In Fig. 2 the apparatus is shown ready for two hand operation by a person standing in front of the same, the right hand handle to be swung in the clockwise direction while the other handle moves counterclockwise. Either spring device, alone, may be used. Also the spring devices may be applied to the bracket with the handles pointing down.

Similarly, either or both spring devices may be applied to either edge of bar 7 and one of the devices may be applied to either vertical edge of upright bar 2.

The variety of exercises that may be carried out with my apparatus is almost endless, but a few will be explained.

It will be noted that with the parts assembled as in Fig. 2, the user either pushes or pulls the handles. At the start the direction of push or pull is outward and downward. Then, after the handles swing down past the horizontal, the push or pull is inward. These movements require cooperation of a variety of muscles of the upper extremities, shoulders, chest and back and, by attempting to carry out these movements, the user is developing coordination of these muscles with each other. This exercise may be performed in a sitting or standing position and may be performed in standing position in combination

with a knee bend to exercise the lower extremities as well as the whole body at the same time.

Both spring devices may be attached vertically to the front of the cross-bar to permit a gentle back stretch by leaning back and flexing the knees (as does the wrestler or boxer in the ring) to limber up. Holding on to the handles causes the springs to provide a soft, gentle cushion. The spring devices also may be attached to the vertical bar 2 for exercises of other various muscle groups. They may be attached at any location on the cross-bar in vertical, upside down position to reverse the spring tension for still more exercises of still other muscle groups.

While both spring devices may be operated together at the same time, they may also be operated in reciprocal succession for exercising still more muscle groups; since, in the latter case, the weight of the body has to shift from one leg to the other, which is one of many important exercises for coordination and endurance.

Only one spring device may be used and the user may face the wall bracket, stand at any angle to the wall bracket, or face in opposite direction and operate the exerciser. Since the user has to take a firm foot hold on the ground to prevent the feet from sliding, many various muscle groups in the lower extremities, the body, such as abdominal, back, waist, hip, and shoulder muscles as well as the muscles of the upper extremity, will be activated and beneficially exercised.

While I have illustrated and described with particularity only a single preferred form of my invention, I do not desire to be limited to the exact details thus illustrated and described, but intend to cover all forms and arrangements that come within the definition of my invention constituting the appended claims.

I claim:

1. A corrective exercising apparatus comprising a stationary supporting member, a spiral spring of the clock spring type adapted to surround said member, a handle attached to and carried by the outer end of the spring, means on the inner end of the spring constructed to interlock with said supporting member and anchor the inner end of the spring while the handle is swung in the plane of the spring.

2. A corrective exercising apparatus comprising a stationary bracket provided with a projecting bar one end of which is free, an open-center, clock type, spiral spring having a handle attached to and carried by its outer end, and a hook on the inner end of the spring to interlock with said bar, and prevent it from moving bodily around the bar, after the spring has been slipped onto the bar to embrace the same.

3. A corrective exercising apparatus comprising a bracket having a bar projecting therefrom, a handle of hand-width length, a spiral spring of the clock spring type connected at its outer end to the handle so that the handle is in the plane of and radial to the spring, and means on the inner end of the spring to interlock with the bar when the spring is slipped onto the bar to embrace the same.

4. A corrective exercising apparatus comprising a bracket provided with a flat, strap-like bar projecting therefrom and free at its outer end, an open center spiral spring of the clock spring type having at its inner end a

straight arm that extends more than half way across the open center and terminates in a return bend to form a hook that embraces an edge of the bar when the spring is slipped onto the bar, and a handle attached to and supported by the outer end of the spring.

5. An apparatus as set forth in claim 4, wherein the handle is of the hand width type and stands radially of the spring.

6. A corrective exercising apparatus comprising a bracket having a base section to be secured to a stationary support, the bracket including a horizontal cross bar in front of and in spaced relation to the base, the end portions of the bar extending rearwardly toward the base but standing clear thereof, and a pair of manually operable spring resistance devices each in the form of a spiral spring having a central opening large enough to permit the device to be slipped onto either free end of the bar and into any position lengthwise of the bar, an anchoring element on the inner end of each spring and within said opening to engage with the bar and hold the said spring end from revolving about the bar, and a radial handle fixed to the outer end of the spring in each device and lying in the same plane as the corresponding anchoring element.

7. A corrective exercising apparatus comprising three separate structures, namely a bracket and a pair of like, manually operable spring resistance devices: the bracket comprising a base member, a cross-like structure containing an upright bar free at its upper end and a cross bar free at both ends, a support for the said structure extending from the base to the lower end of the upright bar, and the ends of the cross bar standing at right angles thereto and extending toward the base; and each resistance device being composed of a spiral spring of the clock spring type adapted to be slipped onto said bars at the free ends of the latter, means on the inner end of the spring to interlock with a bar embraced by the spring to anchor the latter against bodily rotation on the bar, together with a handle fixed to the outer end of and wholly supported by the spring.

8. A corrective exercising device comprising a spiral spring of the clock spring type having an open center, a hook on the inner end of the spring within said open center to interlock with a support embraced by the spring, and a radial handle fixed to and carried by the outer end of the spring.

9. A device as set forth in claim 8, wherein the spring is composed of flat material, flat wound.
